CLAIM

I claim the ornamental design for a seal of a cap for a condiment container, substantially as shown and described.

DESCRIPTION

FIG. 1 is a perspective view of a seal of a cap for a condiment container according to the present design, the seal being shown in a closed position;

FIG. 2 is a front elevational view of the seal of FIG. 1, the sides and rear elevational views thereof being identical;

FIG. 3 is a top view of the seal of FIG. 1;

FIG. 4 is a perspective view of the seal of a cap for a condiment container, shown in an open position;

FIG. 5 is a front elevational view of the seal of FIG. 4, the sides and rear elevational views thereof being identical; and,

FIG. 6 is a top view of the seal of FIG. 4.

The broken lines form no part of the design and are for illustrative purposes only.
